Frank M. Ashley

UNITED STATES PATENT OFFICE.

THOMAS G. JONES, OF EAST ORANGE, NEW JERSEY.

DESIGN FOR A VASE.

54,926.

Specification for Design.

Patented Apr. 20, 1920.

Application filed November 18, 1919. Serial No. 338,978. Term of patent 14 years.

To all whom it may concern:

Be it known that I, THOMAS G. JONES, a citizen of the United States, residing at 81 Beach street, in the city of East Orange, county of Essex, and State of New Jersey, have invented a new, original, and ornamental Design for Vases, of which the following is a specification, reference being made to the accompanying drawing, forming part thereof.

The figure is an elevational view of a vase showing my new design.

The dominant feature of my invention is a form comprising a cylindrical body portion "A", the top of which is of larger diameter, as illustrated by "B" with a curved portion "C" formed intermediate. The said

body portion being ornamented by designs pressed or cut thereon.

My invention particularly comprehends the mounting of the body portion on supports or legs D—D etc., which are spread to cover an area greater than the diameter of the body portion and giving to the vase as a whole a very artistic appearance.

Having thus described my invention, I claim:

The ornamental design for a vase as shown and described.

In testimony whereof, I have hereunto set my hand and seal this 29th day of September, 1919.

THOMAS G. JONES. [L.S.]
